(57) **CLAIM**

The ornamental design for a top frame, as shown and described.

DESCRIPTION

FIG. 1 is a perspective view of a first embodiment of a top frame according to the present invention;

FIG. 2 is a top plan view thereof, the bottom plan view being a mirror image thereof;

FIG. 3 is a front elevational view thereof, the rear elevational view being a mirror image thereof;

FIG. 4 is a left side elevational view thereof, the right side elevational view being a mirror image thereof;

FIG. 5 is a perspective view of a second embodiment of a top frame according to the present invention;

FIG. 6 is a top plan view thereof, the bottom plan view being a mirror image thereof;

FIG. 7 is a front elevational view thereof, the rear elevational view being a mirror image thereof; and,

FIG. 8 is a left side elevational view thereof, the right side elevational view being a mirror image thereof.

The broken lines of FIGS. 1-4, and are for illustrative purposes only and form no part of the claimed design.
